UNITED STATES PATENT OFFICE.

CHARLES H. GATCHELL, OF BOSTON, MASSACHUSETTS.

SOUND-CONDUCTING ATTACHMENT FOR TELEPHONE-RECEIVERS.

1,002,832.

Specification of Letters Patent. Patented Sept. 12, 1911.

Application filed June 24, 1909, Serial No. 504,060. Renewed July 22, 1911. Serial No. 640,019.

To all whom it may concern:

Be it known that I, CHARLES H. GATCHELL, of Boston, in the county of Suffolk and State of Massachusetts, have invented certain new and useful Improvements in Sound-Conducting Attachments for Telephone-receivers, of which the following is a specification.

This invention has for its object to provide an attachment for an ordinary telephone receiver whereby a branched sound conducting tube may be detachably secured to the ordinary ear piece of the receiver, one branch of said tube having an ear piece in close proximity to the receiver, while the other branch is provided with a flexible tube, the free end of which is provided with another ear piece, the arrangement being such that the two ear pieces of the attachment may be applied simultaneously to the two ears of the user of the telephone receiver, or one of said ear pieces may be applied to one ear of the user, and the ear piece on the flexible tube applied at the same time to one of the ears of another person, thus enabling two persons to simultaneously use the receiver.

The invention consists in the improvements which I will now proceed to describe and claim.

Of the accompanying drawings, forming a part of this specification,—Figure 1 represents a perspective view of a telephone attachment embodying my invention. Fig. 2 represents a sectional view of the same applied to a telephone receiver, a portion of which is shown in dotted lines. Fig. 3 represents a side view of a portion of the attachment illustrating the manner of applying the same to a receiver. Fig. 4 represents a side view showing a modification.

In the drawings, 12 represents the ear piece of an ordinary hand telephone or receiver, the same being of the ordinary construction and applied to the body of the receiver in such manner as to confine the usual diaphragm which extends across the sound opening at the center of the concave front side of the ear piece, the ear piece projecting outwardly from the body of the receiver so that its inner side forms an annular shoulder 13 surrounding said body.

14 represents a sheet metal plate formed to cover the front side of the ear piece 12, and bears upon the margin of the same, the said plate when applied to the receiver

constituting the outer side of an air space, the inner side of which is formed by the concave front side of the ear piece.

15 represents a sound conducting tube 60 which extends through the plate 14 and registers with the usual opening at the center of the concave side of the ear piece, said tube being adapted to conduct sound vibrations from the said air space to an ear piece 65 16 which is attached to the outer end of the tube 15. The tube is provided between the plate 14 and ear piece 16 with a branch 17 to which is connected the inner end of a flexible sound conducting tube 18, the free 70 end of which is provided with an ear piece 19.

When the plate 14 is applied to an ordinary receiver, as indicated in Fig. 2, the ear piece 16 is in close proximity to the usual ear piece of the receiver, and may be held against one ear of the user. The ear piece 19 may at the same time be applied to the other ear of the user, thus enabling both ears to be used in receiving sound vibrations 80 from the receiver, the flexible tube 18 being of such length that its ear piece 19 may if desired be applied to the ear of another person so that two persons may simultaneously receive a message through the receiver. 85 Provision is therefore made for enabling the user of a telephone receiver to exclude external noises and utilize both ears in receiving the message, or to enable an assistant to receive the message at the same time, 90 the assistant being enabled to verify the message and to make notes of the same if desired.

I have provided means for enabling the described attachment to be quickly and securely applied to an ordinary telephone receiver, and as quickly removed therefrom, so that the attachment may be applied and discarded with desirable facility, without risk of accidental dislodgment. The said 100 means include hooked coupling members 20 projecting from the upper portion of the edge of the plate 14, these members being integral with the plate 14 and formed to extend across the perimeter of the ear piece 12, and bear upon portions of the rear shoulder 13, the bearing of the members 20 on the ear piece being practically rigid so that when the attachment is in place, they will not yield to an outward pull in a direction 110 lengthwise of the body of the receiver. This practically rigid engagement between the

members 20 and the ear piece is due to the fact that the end portions 21 of the members 20 are so formed that they have an extended flat bearing on the shoulder 13, as indicated in Figs. 2 and 4, hence a pull on the plate 14 in a direction indicated by the arrow *x* in Fig. 2, will press the end portions 21 firmly against the shoulder 13 without having a tendency to spring them outward, and enable them to slip over the margin of the ear piece 12. The lower edge portion of the plate 14 is provided with an adjustable coupling member 22 adapted to pass freely across the edge of the ear piece when the plate 14 is swung in the direction indicated by the arrow *y* in Fig. 3, the member 22, as shown in Figs. 1, 2, and 3, being a curved resilient arm, the curvature of which is such that when the members 20 are engaged with the shoulder 13 in the position shown in Fig. 3, a swinging movement of the plate toward the ear piece 12 will first cause the outer end of the member 22 to spring outwardly and move across the perimeter of the ear piece, the outer portion of the member 22 then springing inwardly behind the shoulder 13, and confining the plate 14 against the ear piece, as indicated in Fig. 2. It will be seen therefore that the plate 14 may be applied to the ear piece 12 by first engaging the members 20 with the rear shoulder of the ear piece, and then swinging the plate inwardly toward the front side of the ear piece until it comes to a bearing thereon, the member 22 adjusting itself to the position required to hold the plate against the ear piece in conjunction with the members 20. The plate may be detached by swinging outwardly the portion carrying the member 22, the latter yielding and passing freely across the perimeter of the ear piece until it reaches the position shown in Fig. 3, when the members 20 may be readily lifted from their engagement with the ear piece.

The branch tube 17 extends in a direction from the center of the device opposite to the hooks 20 so that the weight of the tube 18 and ear piece 19, or an accidental pull thereon, will not dislodge the device because such pull can not act in a direction the reverse of the arrow *y* in Fig. 3.

In Fig. 4, I show a modification in which a two-armed lever is substituted for the spring member 22, said lever comprising a curved inner arm 23 and an outer arm or handle 24 standing at an angle to the arm 23. The lever is provided with ears or trunnions 25 which are adapted to turn in

spring loops 26 formed on the plate 14. When the said lever is in the position indicated by dotted lines in Fig. 4, the arm 23 offers no obstruction to the application of the plate 14 to the ear piece 12, the plate being moved to a bearing on the ear piece by first engaging the members 20 therewith, and then swinging the plate inwardly as above described. The lever is then turned to the position shown by full lines in Fig. 4, the arm 23 being thus caused to engage the rear shoulder of the ear piece 12. The loops 26 are sufficiently resilient to cause them to bear on the sides of the trunnions 25 and yieldingly hold the lever in either of the positions shown.

The ear piece 16 when made of glass is preferably cast or molded with an opening of larger diameter than the tube 15, said opening containing a bushing 30 of yielding material such as cork, or semi-hard rubber adapted to closely fit the wall of the opening and the exterior of the tube, the bushing being cemented, if desired, to the ear piece.

I claim:

A sound conducting attachment for telephone receivers, comprising a flat plate adapted to bear on the rim of the ear piece of an ordinary receiver, and provided at one portion of its edge with practically rigid hooked coupling members adapted to engage the rear shoulder of the ear piece of the receiver, and permit a swinging movement of the plate to a bearing on the front of the ear piece, and at another portion of its edge with an adjustable coupling member adapted to pass freely across the edge of the ear piece when the plate is swinging to a bearing thereon, and to engage said rear shoulder to confine the plate against the ear piece, a sound conducting tube having a branch and having one end extending through the plate and having an ear piece at its other end, the said ear piece being at a distance from the flat plate to permit the branch to extend laterally without contact with either the flat plate or outer ear piece, and a flexible tube connected at one end with said branch and having an ear piece at its free end.

In testimony whereof I have affixed my signature, in presence of two witnesses.

CHARLES H. GATCHELL.
